UNITED STATES PATENT OFFICE

JESSE E. McBRIDE, OF DETROIT, MICHIGAN, ASSIGNOR TO PALMER-BEE COMPANY, OF DETROIT, MICHIGAN, A CORPORATION OF MICHIGAN.

TROLLEY CONVEYER.

Application filed January 2, 1923. Serial No. 610,331.

To all whom it may concern:

Be it known that I, JESSE E. McBRIDE, a citizen of the United States of America, residing at Detroit, in the county of Wayne and State of Michigan, have invented certain new and useful Improvements in Trolley Conveyers, of which the following is a specification, reference being had therein to the accompanying drawings.

10 The invention relates to trolley conveyers and refers more particularly to the power propelled type of trolley conveyer. One of the objects of the invention is to provide a conveyer in which an I-beam track supports a power propelled trolley which is secured to a flexible draft connection instead of being merely propelled thereby by a projecting finger or pusher. Other objects are the provision of a conveyer in which the trolley is provided with means for limiting its upward movement relative to the track; in which the track is vertically curved and the trolley is provided with means engageable with the track for maintaining the trolley in a substantially radial position relative to the curve of the track; and in which the trolley is attached to the chain by a link connecting pin so that the side frames of the trolley are free to rotate on this pin removing any eccentric or any other stresses on the adjacent link connecting pin other than due to the straight pull of the chain. A further object of the invention is the provision of means upon the trolley for catching dirt falling from the track to thereby protect the work being carried by the trolley.

With these as well as other objects in view, the invention resides in the novel features of construction and combinations and arrangements of parts as more fully hereinafter set forth.

In the drawings:

Figure 1 is a side elevation of a portion of a power propelled trolley conveyer embodying my invention;

Figure 2 is a sectional plan view thereof;

Figure 3 is a cross section on the line 3—3 of Figure 1;

Figure 4 is a side elevation of a modified construction;

Figure 5 is a perspective view of a portion on the track.

1 is an I-beam track curved in a vertical plane, and 2 is the trolley suspended from

the track and having the spaced side frames 3 and 4, preferably of T-shaped cross section, and rollers 5 and 6 engaging the lower flanges of the I-beam and journaled upon the stub shafts 7 and 8 in the upper enlarged ends of the side frames 3 and 4 respectively. 9 is a pin preferably mounted rotatably in and extending between the lower ends of the side frames 3 and 4.

10 is the propelling chain secured to the trolley for advancing the same along the track. This chain has the links 11 and 12 which are rotatably connected to the pin 9 so that the latter constitutes a link connecting pin. The link connecting pins engaging the opposite ends of the links 11 and 12 extend at right angles to the pin 9, the arrangement being such that the propelling chain is flexible in both horizontal and vertical directions. 13 is a depending clevis which preferably rotatably engages the central portion of the pin 9 between the bifurcations 14 of the link 12, these bifurcations being embraced by the bifurcations 15 of the link 11, the arrangement being such that but very limited movement of the parts between the side frames is possible.

15 In the event that the weight carried by the trolley is not sufficient to counteract the tendency of the propelling chain to straighten out while the trolley is passing around a depressed portion of the I-beam track, the trolley tends to move upwardly relative to the track. This upward movement is, however, prevented by suitable anti-friction means upon the trolley engageable with the underside of the track. As shown in Figure 1 particularly this anti-friction means comprises the pair of rollers 16, each of which is journaled on the separator bushing 17 extending between the side frames 3 and 4 and holding the same spaced apart and surrounding the bolt 18, the threaded end of which is engaged by the nut 19 for securing the side frames against the ends of the separator. These rollers coming into engagement with the lower side of the track prevent any further upward movement of the trolley, and since there are rollers upon opposite sides of the vertical plane passing through the axes of the supporting rollers 5 and 6, the trolley is maintained in a substantially radial position relative to the curve of the track and prevented from mov-

ing angularly to fall back against the propelling chain when passing through the vertical curves.

Since the work is carried directly underneath the I-beam track and the action of the supporting rollers on the lower flanges of the track produce a metallic dust and since these rollers might also push off other dirt which has settled on the lower flanges, it is very important to have provision for catching the dirt to protect the work being carried by the conveyer especially if the work is being painted or enamelled. With this object in view, I have provided the horizontally extending shelves 20 preferably cast integral with the side frames 3 and 4 respectively and located below the I-beam track and extending there-beneath and laterally beyond the peripheries of the supporting rollers 5 and 6, the arrangement being such that any dirt caused to fall from the track by the rollers or falling from the rollers will fall upon these shelves.

For the purpose of maintaining the trolley in a vertical position while its supporting rollers are passing over the gap between the stationary I-beam track 1 and the adjustable portion of the I-beam track 21 upon the take-up carriage carrying an end sprocket over which the propelling chain passes, I have provided the guide 22 below the adjacent ends of the tracks 1 and 21 and preferably formed of angle bars. These bars are positioned to engage the sliding shoes 23 upon the lower ends of the side frames 3 and 4 and to support the trolley while passing from one track to the other. In the present instance, I have shown the bars in position to support the trolley with its supporting rollers raised from the lower flanges of the tracks, although it is apparent that the trolley may be supported in some lower position. Each shoe is preferably formed of a lateral flange integral with its respective trolley side frame and having upturned ends. Since each shoe has an extended longitudinal bearing upon its angle bar and since the propelling force applied to the trolley is immediately above the bearing surfaces of the shoes, the trolley will be maintained in vertical position.

In the modified construction shown in Figure 4, 24 is an I-beam track and 25 the trolley suspended therefrom and having spaced side frames which are rigidly connected to the attachment link 26 of the propelling chain 27. For limiting the upward movement of the trolley relative to the I-beam track, I have provided the roller 28 adapted to engage the underside of the track and located intermediate the spaced side frames of the trolley and having its axis of rotation in vertical alignment with the axes of rotation of the rollers 29, which carry the side frames.

What I claim as my invention:

1. The combination with a track, of a trolley suspended from said track at one longitudinal point in its length, and means upon said trolley, offset from the vertical plane 70 through the point of suspension of said trolley and engageable with said track for limiting the upward movement of said trolley relative to said track.

2. The combination with a track, of a 75 power propelled trolley suspended from said track at one longitudinal point in its length, means secured to said trolley for propelling the same, and means upon said trolley, offset from the vertical plane through the point 80 of suspension of said trolley and engageable with said track for limiting the upward movement of said trolley relative to said track.

3. The combination with a track, of a 85 trolley suspended from said track at one longitudinal point in its length, and an anti-friction member upon said trolley, offset from the vertical plane through the point 90 of suspension of said trolley and engageable with said track for limiting the upward movement of said trolley relative to said track.

4. The combination with a track, of a 95 trolley suspended from said track at one longitudinal point in its length, and means upon opposite sides of the vertical plane through the point of suspension of said trolley engageable with said track for limiting the upward movement of said trolley 100 relative to said track.

5. The combination with a track, of a trolley suspended from said track at one longitudinal point in its length and having 105 a supporting roller in engagement therewith, and rollers upon said trolley and at opposite sides of the vertical plane passing through the axis of said supporting roller, said last-mentioned rollers being engageable with the under side of said track for limiting the upward movement of said trolley 110 relative to said track.

6. The combination with a track curved in substantially the vertical plane, of a power propelled trolley suspended from said track at one longitudinal point in its length, means secured to said trolley for propelling the same, and means upon said trolley and at opposite sides of the vertical plane passing through the point of suspension of said trolley engageable with the lower side of 115 said track for limiting the upward movement of said trolley relative to said track.

7. The combination with a track having a central web and outstanding track flanges and curved in a substantially vertical plane, of a power propelled trolley suspended from said track flanges at one longitudinal point in their lengths and comprising side frames, 120 rollers upon said side frames engaging the 125

lower flanges, said rollers having their axes in the same plane, rollers upon said side frames below said track and engageable with the lower side thereof for limiting the 5 angular movement of said trolley relative to said track, and a draft connection secured to said trolley.

8. The combination with a track, of a trolley supported upon said track and including a frame and means rigid with said frame adjacent to and below said track for catching and retaining dirt falling from said track.

9. The combination with a track, of a trolley suspended from said track and including a side plate, a support for said side plate engaging said track, and a shelf upon said side plate below said track and support and extending beyond said support.

10. The combination with a track, of a trolley suspended from said track and including a side plate, a roller carrying said side plate and engaging said track, and a horizontally extending shelf below said 25 track and roller and extending beyond the periphery of said roller.

11. The combination with a track, of a trolley suspended from said track and including spaced side frames, supports for said 30 side frames in engagement with said track, a pin connecting said side frames below said track, chain links pivotally engaging said pin intermediate said side frames, and a load sustaining member engaging the central portion of said pin.

12. The combination with a track, of a power propelled trolley suspended from said track and including spaced side frames, supports at the upper ends of said side frames 40 engaging said track, a rotatable pin extending between the lower ends of said side frames, chain links pivotally connected to said pin intermediate said side frames, and a clevis rotatably engaging said pin intermediate said chain links.

13. The combination with a track, of a trolley suspended from said track and including spaced side frames, rollers at the upper ends of said side frames for support-

ing the same upon said track, means at the 50 lower ends of said side frames for carrying a load, a separator bushing between said side frames intermediate their ends and below said track, and a roller upon said bushing and engageable with said track upon upward movement of said trolley relative to said track.

14. The combination with aligned tracks having a gap between their adjacent ends, of a trolley adapted to be suspended from said 60 tracks, a member upon said trolley provided with an extended bearing surface, and a guide below said tracks adapted to engage the bearing surface of said member and support the trolley while passing over the gap 65 between the ends of said tracks.

15. The combination with aligned tracks having a gap between their ends, of a trolley adapted to be suspended from said tracks and including a side frame and a supporting 70 roller engageable with said tracks and carrying said side frame, a guide below the gap between the ends of said tracks, and a sliding shoe upon said side frame engageable with said guide and adapted to carry said 75 trolley while passing over the gap.

16. The combination with aligned tracks having a gap between their ends, of a trolley adapted to be suspended from said tracks and comprising side frames and rollers upon 80 said side frames and adapted to engage said tracks, bars below the gap between the ends of said tracks, sliding shoes upon the lower ends of said side frames engageable with said bars and adapted to carry said trolley 85 while passing over the gap between the track ends, and a propelling chain connected to said trolley adjacent to said sliding shoes.

17. The combination with a track, of a trolley suspended from said track, means 90 engageable with said track for supporting said trolley and means engageable with said track for limiting the upward movement of said trolley relative to said track, one of said means being at opposite sides of the vertical 95 plane passing through the other means.

In testimony whereof I affix my signature.

JESSE E. McBRIDE.
